US00D817212S

(12) **United States Design Patent** (10) **Patent No.:** **US D817,212 S**
(45) **Date of Patent:** **** May 8, 2018**

(54) **NECKLACE**

- (71) Applicant: **ACE LIGHT & ELECTRONIC TECH(NINGBO) CO., LTD.**, Ningbo, Zhejiang Province (CN)
- (72) Inventor: **Yanbei Qin**, Ningbo (CN)
- (73) Assignee: **ACE LIGHT & ELECTRONIC TECH (NINGBO) CO., LTD.**, Ningbo (CN)

(**) Term: **15 Years**

(21) Appl. No.: **29/597,675**

(22) Filed: **Mar. 18, 2017**

(30) **Foreign Application Priority Data**

- Sep. 23, 2016 (CN) 2016 3 0479465
- (51) **LOC (11) Cl.** **11-01**
